(57) **CLAIM**

The ornamental design for an absorbent article with a pattern, as shown and described.

DESCRIPTION

FIG. 1 is a perspective view of an absorbent article with a pattern;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The stitching shown in FIGS. 1-2 and FIGS. 4-6 that rest on the surface itself form a lace pattern and form no part of the claimed design. The surfaces that rest underneath the lace pattern form a part of the claimed design.
